US0D1085054S

(12) **United States Design Patent** (10) Patent No.: **US D1,085,054 S**
(45) Date of Patent: ** Jul. 22, 2025

(54) **LOUDSPEAKER**

- (71) Applicant: **Harman International Industries, Incorporated**, Northridge, CA (US)
- (72) Inventors: **David Dixon**, Grosse Pointe, MI (US); **Jose Tomas DeLuna**, Canton, MI (US)
- (73) Assignee: **Harman International Industries, Incorporated**, Northridge, CA (US)
- (**) Term: **15 Years**
- (21) Appl. No.: **29/925,177**
- (22) Filed: **Jan. 23, 2024**

Related U.S. Application Data

- (62) Division of application No. 29/821,598, filed on Dec. 30, 2021, now Pat. No. Des. 1,049,079.

(57) **CLAIM**

The ornamental design for a loudspeaker as shown and described.

DESCRIPTION

FIG. 1 is a top plan view of a loudspeaker showing the new design;

FIG. 2 is a bottom plan view thereof;

FIG. 3 is a side elevational view thereof;

FIG. 4 is an opposite side elevational view thereof;

FIG. 5 is a rear elevational view thereof; and,

FIG. 6 is a front elevational view thereof.

The broken lines, including the broken line circles depicting openings of the loudspeaker grille, illustrate portions of the loudspeaker that form no part of the claimed design.

1 Claim, 3 Drawing Sheets
